UNITED STATES PATENT OFFICE.

EDWARD J. MOORE, OF BALTIMORE, MARYLAND.

MEANS FOR CLOSING BOILER-TUBES.

SPECIFICATION forming part of Letters Patent No. 278,998, dated June 5, 1883.

Application filed March 14, 1883. (No model.)

To all whom it may concern:

Be it known that I, EDWARD J. MOORE, of the city of Baltimore, and State of Maryland, have invented certain Improvements in Means 5 for Closing Boiler-Tubes, of which the following is a specification.

This invention relates to means for closing the ends of tubes, and particularly tubes used in sectional steam-boilers.

10 The said invention consists in combining with a tube the end of which is cut so as to present, practically, a square edge a closing-cap having an annular V-groove, into which the end of the said tube is inserted, and a bolt 15 and nut to force the tube and cap closely in contact to form a tight joint, as hereinafter more particularly described.

In the accompanying drawings, forming a part hereof, Figure I is a sectional view of a 20 part of a sectional boiler leg and tube, the latter being closed in accordance with my invention. Fig. II is an inside view of the cap. Figs. III and IV illustrate certain modifications in the construction of the cap.

25 Similar letters of reference indicate similar parts in all the views.

A is a part of a sectional boiler-leg, which is shown as consisting of two plates, *a*, separated by a space, *b*.

30 B is a tube which passes through the plates or sheets *a*, in which it is expanded.

C is a cap having an annular V-groove, *c*, which is forced in contact with the end of the tube B by means of a bolt, *d*, and nut *e*. In 35 Fig. I the bolt *d* is of the anchor description, and secures the cap to the tube independently of the cap at the other end of the tube, while in Figs. III and IV the bolt is intended to pass

entirely through the tube and secure two caps. In Figs. I, II, and III the groove *c* is of a 40 strictly V-shape; but the apex of the angle is of no value, as it is not in contact with the tube. The groove can therefore be of circular or nearly circular shape, as shown in Fig. IV, which gives two points of contact with the 45 tube, and forms two joints, as in the V-groove.

It will be understood that the principal advantage of the invention consists in that when the groove and the tube are brought to the proper diameters no difficulty is experienced in 50 forming a water and steam tight joint with only a slight strain on the bolt, as the sharp angles on the tube end readily conform to the grooved surface of the cap. If preferred, the nut *e* may be a part of the cap C.

55

I claim as my invention.

1. In combination with a tube with a square-faced end or edge, a cap having an annular groove, which presents an angular surface to the edge of the tube, and a bolt and nut to 60 force the cap and tube closely in contact to form a tight joint, substantially as specified.

2. A sectional boiler-tube which extends through a water-leg and is secured within the two walls or plates of the same, as described, 65 having a square-faced end or edge, combined with a closing-cap having an annular V-groove, into which the end of the said tube is inserted, and a bolt and nut to force the cap and tube closely in contact to form a water-tight joint, 70 substantially as specified.

EDWARD J. MOORE.
